(57) **CLAIM**

The ornamental design for a computer, as shown and described.

DESCRIPTION

FIG. 1 is a perspective view of a computer showing our new design;

FIG. 2 is a top plan view thereof;

FIG. 3 is a front elevational view thereof;

FIG. 4 is a right side elevational view thereof;

FIG. 5 is an enlarged partial perspective view thereof along the lines 5-5 and 5-5 of FIG. 1;

FIG. 6 is an enlarged partial top plan view thereof along the lines 6-6 and 6-6 of FIG. 2;

FIG. 7 is an enlarged cross-sectional view thereof cut along the lines 7-7 of FIGS. 4 and 6;

FIG. 8 is an enlarged cross-sectional view thereof cut along the lines 8-8 of FIGS. 3 and 6;

FIG. 9 is a perspective view thereof wherein the key is pressed;

FIG. 10 is a top plan view thereof;

FIG. 11 is a front elevational view thereof;

FIG. 12 is a right side elevational view thereof;

FIG. 13 is an enlarged partial perspective view thereof along the lines 13-13 and 13-13 of FIG. 9;

FIG. 14 is an enlarged partial top plan view thereof along the lines 14-14 of FIG. 10;

FIG. 15 is an enlarged cross-sectional view thereof cut along the lines 15-15 of FIGS. 12 and 14;

FIG. 16 is another enlarged cross-sectional view thereof cut along the lines 16-16 of FIG. 15; and,

FIG. 17 is an enlarged cross-sectional view thereof cut along the lines 17-17 of FIGS. 11 and 14.

The evenly-spaced broken lines illustrate unclaimed portions of the computer and form no part of the claimed design. The single dot-dash broken lines define boundaries of, and are not included in the claimed design. The double dot-dash broken lines show the boundaries of the enlarged figures that match the portions of the computer shown with arrows and corresponding figure numbers. The double-dot-dash broken lines do not form the claimed design.
